PRICE TAG

Alonzo K. Marsh, Summit, N. J., assignor to A. Kimball Company, New York, N. Y., a corporation of New York

Application March 19, 1937, Serial No. 131,763

2 Claims. (Cl. 40—25)

This invention relates to price tags of the type intended to be secured to articles of merchandise in such manner that they cannot be removed therefrom without detection.

5 It is an object of the invention to provide a tag of this type which shall have improved safeguards against unauthorized removal, which may be easily applied to the merchandise, and which may be easily removed therefrom.

10 Other objects and advantages of the invention will appear hereinafter.

A preferred embodiment of the invention selected for purposes of illustration is shown in the accompanying drawing, in which,

15 Figure 1 is a perspective view of the tag.

Figure 2 is a plan view showing the staples clinched.

Figures 3 and 4 are plan views showing the front and back faces of the tag.

20 Figure 5 is a longitudinal section on the line 5—5 of Figure 1.

Figure 6 is a similar section showing the method of removing the tag.

Referring to the drawing, the tag comprises a 25 body portion 1 of any convenient size, but usually of considerable area and length in order to provide adequate space for printing. At one end of the body portion, the paper or cardboard of which the tag is formed is folded along fold line 2 to provide a flap 3. It is then reversely folded along fold line 4 to provide flap 5. Finally it is folded again in the same direction along fold line 6 to provide end flap 7 which lies between flaps 3 and 5.

30 35 End flap 7 is provided with the usual attaching staple 8 of any suitable construction, and the flap 3 is provided with suitable apertures 9 registering with the legs of the staple so that the staple legs may be passed through the merchandise to be tagged, then through said apertures, and clinched on the opposite face of flap 3, thus securing the tag to the merchandise.

Secured to the body portion 1 and to the flap 3 in registering positions are two parts 10 and 11 of 40 a lock seal device, such, for example, as illustrated in Laenger Patent No. 1,916,003. As set forth in said patent the interlocking parts may be readily snapped together, but once together cannot be separated without mutilating the seal.

45 50 If desired, the seal part 10 may be surrounded by a line of perforations 12 which weaken the paper, so that when it is desired to remove the tag, the body portion 1 may be lifted to tear the

paper along said weakened line, as illustrated in Figure 6, thus exposing the staple legs for removal.

In use, the merchandise is inserted between the flaps 3, 5 and 7 as shown, and the staple legs are 5 passed through and clinched. The lock seal is then snapped into place. It will be observed that due to the provision of the end flap 7 the portion of the staple which is attached to flap 7 is completely covered by flap 5 and no part of it is 10 available for tampering. The staple legs are covered by the body portion 1 and cannot readily be reached for tampering. The tag also has advantages over such forms of tags as are illustrated in Patents No. 1,054,927 and No. 1,680,459 15 in which metal eyelets are used to secure the flaps together, because the merchandise can be inserted the full depth of the flaps without danger of damage from the insertion of the eyelet.

It will be understood that the invention may 20 be variously modified and embodied within the scope of the subjoined claims.

I claim as my invention:

1. A price tag comprising a body portion and a series of connected flaps at one end thereof, 25 the flap adjoining the body portion being folded in one direction, the second flap being folded in the opposite direction, and the third flap being folded back to lie between the first and second flaps, a staple secured to said third flap, said 30 first flap being provided with an aperture registering with said staple so that the legs of said staple may pass through said first flap and be clinched on the other side, and means for securing said body portion to said first flap to thereby 35 cover said staple legs.

2. A price tag comprising a body portion and a series of connected flaps at one end thereof, the flap adjoining the body portion being folded in one direction, the second flap being folded in the opposite direction, and the third flap being folded back to lie between the first and second flaps, a staple secured to said third flap, said 40 first flap being provided with an aperture registering with said staple so that the legs of said staple may pass through said first flap and be clinched on the other side, and a lock seal comprising two parts, one of which is secured to said body portion and the other secured to said first flap in registering position for securing said body portion to said first flap to thereby cover said 45 staple legs.

ALONZO K. MARSH.
